UNITED STATES PATENT OFFICE.

FRANK J. STEVENS, OF SAN BERNARDINO, CALIFORNIA.

ADVERTISING DEVICE.

Application filed April 17, 1920. Serial No. 374,702.

To all whom it may concern:

Be it known that I, FRANK J. STEVENS, a citizen of the United States, residing at San Bernardino, in the county of San Bernardino and State of California, have invented certain new and useful Improvements in an Advertising Device, of which the following is a specification.

This invention relates to advertising ma-

10 chines, and the primary object of the invention is to provide an improved advertising device embodying a plurality of stationary advertisements and a plurality of movable advertisements, the movable adver-
15 tisements being arranged in such a manner in relation to the stationary advertisements that attention will be attracted to all of the advertisements.

Another object of the invention is the

20 provision of an improved display or advertising device having a plurality of stationary advertising cards, a plurality of display windows arranged between certain of the advertising cards, and a movable
25 endless belt or ribbon having a plurality of advertisements associated therewith, arranged to move behind the display window, the belt or ribbon being arranged in such a manner that the advertisement on the belt
30 moves in different directions behind every other display window.

A further object of the invention is to provide an improved advertising device embodying an endless belt having associated
35 therewith a plurality of advertisements, the belt being arranged to move in rear of a plurality of display windows, the belt being arranged in relation to the windows in such a manner that only one face of the belt
40 is used for advertising matter.

A further object of the invention is the provision of an improved advertising device which can be used for indoor and outdoor advertising purposes, the same includ-
45 ing a body or cabinet having a hinged front wall or closure carrying a plurality of stationary display cards, and a plurality of display windows, the cabinet having means associated therewith for moving an endless belt carrying advertisements in rear of said display windows.

A still further object of the invention is to provide an inexpensive advertising medium which will be durable and efficient in
55 use, one that is simple and easy to manu-

facture, and one which can be placed upon the market at a reasonable cost.

With these and other objects in view the invention consists in the novel construction, arrangement and formation of parts, 60 as will be hereinafter more specifically described, claimed and illustrated in the accompanying drawings, forming a part of this specification, in which drawings:

Figure 1 is a front elevation of the im- 65 proved display device.

Figure 2 is a transverse section through the same.

Figure 3 is a front elevation of the frame and rolls for supporting the endless belt 70 or ribbon, the same being shown removed from the cabinet.

Figure 4 is a longitudinal section through the frame and rolls taken on the line 4-4 of Figure 3, the display ribbon or belt being shown trained around the rolls and in section, and 75

Figure 5 is an enlarged fragmentary detail section through the frame showing an elevation of one of the rolls. 80

Referring to the drawings in detail, wherein similar reference characters designate corresponding parts throughout the several views, the letter A indicates the improved display device, which includes a 85 cabinet or the like B having a frame C associated therewith for supporting a plurality of rotatable rollers D for guiding the endless belt or ribbon E.

The cabinet B may be constructed of any 90 preferred material and of any desired shape or configuration, and as shown in the drawings includes the rear wall 10, the side walls 11, and the hinged front wall 12. The hinged front wall 12 may be locked 95

in closed position, if so desired, so as to prevent unauthorized persons from gaining access to the interior of the cabinet. The hinged closure 12 is provided with a frame 13, which is subdivided in a plurality of spaces 14 for the reception of cards 15 bearing suitable advertisements by a plurality of transverse and longitudinal cleats or bars 16 and 17. The longitudinally ex- 100 tending bars 17 are arranged in parallel 105 relation to one another and to the longitudinal side bars of the frame 13 as shown. The longitudinal bars define three rows of advertising spaces and the central row is provided with a plurality of display win- 110

dows 18, 19, 20 and 21, which are arranged intermediate the stationary display cards 15. A suitable glass is placed in front of the cards, so as to protect the same from 5 injury.

The frame C for supporting the rollers D for the advertising belt or ribbon E can be formed of any preferred material and in any desired manner, but the same is preferable 10 formed of metal and moulded to provide the relatively long rear wall 22 and the side walls 23 and 24. The rear wall 22 and the side walls 23 and 24 are preferably formed of an open frame work arrangement so as 15 to lighten the weight of the frame C and save material in the making thereof. The side walls 23 and 24 are cast in such a manner as to provide a plurality of spaced pairs of bearing arms 25, 26, 27 and 28 and these 20 spaced pairs of bearing arms rotatably support pairs of rollers 29, 30, 31, and 32. The pairs of rollers 29, 30, 31 and 32 are arranged directly in rear of the display windows 18, 19, 20 and 21 and serve to guide the 25 display belt or ribbon E in rear of the said display windows.

The guide rollers D for the endless belt or ribbon E include the spaced pairs of rollers 29, 30, 31 and 32, and upper and lower rollers 33 and 34, which form means for dividing the endless belt into a front run and a rear run. To make the advertising matter on the belt move in opposite directions behind the display windows 18, 19, 20 and 21, the belt 35 or ribbon E is brought back and forth, so that in certain of the display windows the front run of the belt or ribbon E will be seen, while in other windows the rear run of the belt or ribbon E will be seen. To deflect 40 the course of the runs of the belt or ribbon E a plurality of oppositely inclined rollers 36, 37, 38, 39, 40, 41, 42 and 43 are provided. These rollers are mounted in suitable bearings 44 carried by the inner surface of the 45 side walls 23 and 24 of the frame. The side wall 23 is provided with a pair of spaced outstanding bearings 45, which rotatably support the guide rollers 46. These bearings 45 are located adjacent to the trans- 50 verse axis of the frame upon one side thereof, while the wall 24 has arranged adjacent to and at one side of the transverse axis a pair of spaced bearings 47 which rotatably support the guide rollers 48. The side walls 23 55 and 24 adjacent to their opposite ends are also provided with bearings 49 and 50, which rotatably support rollers 51 and 52. The outer rollers of the pairs of rollers 29 and 32 are provided with pulley wheels 53 around 60 which is adapted to be trained a suitable drive belt for moving the display belt or ribbon E. The rollers of each pair of rollers 29 and 32 are preferably driven by an electric motor which may be geared down so that 65 the belt or ribbon E will move at a relatively

slow rate of speed and thus give ample time for the reading of each advertisement printed thereon as the same moves behind the display windows 18, 19, 20 and 21.

The rollers of the pairs 29, 30, 31 and 32 70 and the inclined rollers 36, 37, 38, 39, 40, 41, 42 and 43 and the side rollers 46, 48, 51, and 52 are formed slightly different so as to be best adapted for the work with which they are intended to be used, but all of the rollers 75 are substantially the same and include a body 55 and a shaft 56 which has its terminals mounted in the bearings. Also certain of the rollers are provided with guard flanges 57 to prevent the belt or ribbon E 80 from slipping off of the same and with nuts 58 which tend to space the rollers from the bearings.

The belt or ribbon E may be formed of any preferred material, either of tough paper or 85 fabric, such as linen and the same is trained around the rollers D in the following manner. In following the ribbon E down the frame, the same is trained over the pair of rollers 29 and behind the window 18 and is 90 then brought under the inclined roller 37 and twisted to the side of the frame and over the rollers 48 and to one side of the display window 19 until the same reaches the inclined roller 40 where the same is threaded 95 into the frame and under the roller 40 and over the rollers 31 in rear of the display window 20 and then under the inclined roller 41 and over the side roller 52 and over the incline roller 43 and under the 100 roller 34 and then up in front and around the spaced rollers 32 in rear of the display window 21. The belt then extends under the inclined roller 42 and is brought to one side of the machine over 105 the pairs of rollers 46 to one side of the display window 20 and then under the inclined guide roller 39 in front and over the pair of rollers 30 in rear of the display window 19 and then in rear of the guide 110 roller 38 and over the roller 51 and over the guide roller 36 and under the roller 33 back to the upper pair of rollers 29.

To pick up the slack in the belt or ribbon E belt tighteners 59 and 60 are arranged at 115 the upper and lower end of the frame C and each of the tighteners 59 and 60 includes a pair of spaced arms 61 which are pivotally secured to the side walls 23 and 24 of the frame C as at 62. The outer terminals of the pairs of arms 61 carry rollers 63 which engage the inner face of the belt. Suitable springs 64 engage the arms 61 and normally tend to move the rollers 63 in opposite directions.

From the foregoing description, it can be seen that an improved display mechanism is provided in which a plurality of display windows are arranged intermediate the stationary display cards, the display windows 130

having arranged in rear thereof a movable endless belt for carrying suitable advertisements, the whole arrangement providing a novelty advertising device which will effectively attract the attention of a passer by.

While only four display windows have been shown, it is to be understood that any number of the same may be provided as desired by increasing or decreasing the length 10 of the frame, and if so desired a plurality of frames may be provided and arranged side by side so that a row of stationary advertisements will be provided and then a row of movable advertisements.

Changes in details may be made without departing from the spirit or scope of the invention; but,

I claim:

1. An advertising device comprising a frame, a plurality of stationary display cards arranged in the frame, a plurality of spaced display windows carried by the frames arranged intermediate the display cards, a movable display device disposed in rear of the display windows and arranged to move in opposite directions behind certain of said windows.

2. An advertising device comprising a frame, a plurality of longitudinally extending rows of display cards arranged in the frame, the intermediate rows of display cards being arranged in spaced relation, and a movable belt arranged in rear of said display cards and arranged to be seen through the spaces intermediate the display cards, and advertisements carried by said belt.

3. An advertising device comprising a plurality of spaced stationary advertisements, a plurality of display windows arranged between the advertisements, an endless belt having advertisements associated therewith and arranged in rear of the stationary advertisements, and guide rollers arranged to guide the front and rear runs of the belt in front of the display windows.

4. An advertising device comprising a plurality of display cards, a plurality of display windows arranged between the cards, an endless belt arranged in rear of the display cards and having advertisements thereon, and a plurality of guide rollers arranged to guide the front and rear runs of the belt by

said display windows, certain of said guide rollers arranged in a horizontal plane and others at an angle to the horizontal.

55

5. In an advertising device, a frame, a plurality of pairs of spaced rollers carried by the frame, end rollers carried by the frame and arranged in rear of the pairs of spaced rollers, an endless belt trained around said rollers to move the front and rear runs of the belt in alignment with each other at spaced points.

6. In an advertising device, a frame, a plurality of pairs of spaced rollers carried by the frame, end rollers carried by the frame and arranged in rear of the first rollers, a plurality of oppositely inclined guide rollers carried by the frame and arranged intermediate the first mentioned rollers, and spaced rollers carried by the sides of the frame and arranged intermediate the inclined rollers, and an endless belt trained around said rollers.

65

7. In an advertising device, a frame including a rear wall and side walls, the side walls having a plurality of pairs of spaced bearings therein, a plurality of pairs of spaced rollers carried by the bearings and arranged intermediate the side walls, a pair of spaced rollers carried by the side walls and arranged intermediate the same and in rear of the pairs of spaced rollers, oppositely inclined guide rollers carried by the sides of the frame and arranged intermediate the same and in rear of the pairs of spaced rollers, and intermediate the second mentioned rollers, and spaced rollers carried by the opposite faces of the side walls of the frame and arranged beyond the first mentioned 80 rollers, and a guide belt trained around said rollers.

85

8. An exhibitor having sign openings to be viewed simultaneously, an endless exhibiting member, and means training different 90 portions of the member for movement in different directions in exhibition positions at different openings simultaneously.

95

9. An exhibitor having an endless exhibiting member and means operable to move 100 portions thereof in opposite directions simultaneously in substantially the same plane.

FRANK J. STEVENS.
